UNITED STATES PATENT OFFICE

WALTER J. BRADFISH, OF EAGLE RIVER, WISCONSIN

ELECTRIC HEATER

Application filed March 4, 1931. Serial No. 520,106.

This invention relates to certain new and useful improvements in electric heaters, and the primary object of this invention is to provide an electric heater capable of application to a pipe, such as a water pipe, oil pipe or the like for heating the fluid flowing through the pipe.

A still further object of the invention is to provide a heater of the above mentioned character which is especially but not necessarily designed for application to the water pipe leading from the radiator to the internal combustion engine of an automobile for heating the water circulating through the cooling system of the internal combustion engine to facilitate starting of the engine in cold weather.

A still further object of the invention is to provide a heater of the above mentioned character, which may be also suitably applied to the crank case of an internal combustion engine for heating the oil therein, or to a frozen radiator of an automobile for thawing out the radiator.

A still further object of the invention is to provide a heater of the character above mentioned, which can be also applied to the intake manifold of an internal combustion to aid in starting the same during cold weather, and further to provide such a heater which can also be used domestically for thawing frozen water pipes in buildings, and dwellings.

Other objects and advantages of the invention will become apparent during a study of the following description taken in connection with the accompanying drawings wherein:

Figure 1 is an elevational sectional view of a portion of a vehicle showing the heater as applied to the water pipe leading from the radiator of the vehicle to the internal combustion engine.

Figure 2 is a transverse sectional view taken substantially on line 2-2 of Figure 1.

Figure 3 is a perspective view of the heater, the socket of an electric cord being shown separated from the terminals of the heating element of the heater.

Figure 4 is a bottom plan view of the heat-

er, the same being shown as applied to a pipe.

With reference more in detail to the drawings, it will be seen that the heater comprises a substantially semi-cylindrical casing formed of metal or any other suitable material, and including a pair of spaced semi-cylindrical walls 5 and 6 connected by longitudinal walls 7 and end walls 8. The walls of the hood thus provide an enclosed chamber within which is arranged an electric heating element extending for the full length of the hood and including a heating wire 9 embedded in suitable material 10, suitable insulating material being interposed between the heating element and the wall 5 of the hood.

Oppositely disposed closure gates for the hood are provided, and these gates designated by reference numeral 12 are hinged to the walls 7 as at 13.

The hood is adapted to embrace a pipe P, which pipe P may be that pipe leading from the radiator R to the internal combustion engine E of an automobile.

When the hood is so mounted on the pipe P, the same is retained in position on the pipe by swinging the gates 12 toward one another to a position opposite the open side of the hood to engage a portion of the pipe P as suggested in Figure 2.

A handle member 14 is preferably formed from a single length of spring wire, the wire being bent into a substantial V, and having the legs 15 thereof at their free ends terminating in lateral projections 16. Projections 16 are adapted to be disposed on opposite sides of the hood and are bowed longitudinally to conform somewhat with the shape of the hood. Lateral extensions 16 at their free end terminate in inwardly directed terminals 17 hingedly connected to the gates 12 as at 18 in any suitable manner.

A retaining loop 19 is slidably engaged with the legs 15, and from a study of Figure 3, it will be seen that when the loop 19 is slid longitudinally toward the free end of the leg, said legs will be moved inwardly toward one another thus forcing the gates 12 inwardly toward one another to assume the position shown in Figure 2. Loop 19 frictionally en-

gages the legs, will serve to retain the gate 12 in said position.

The wire 9 of the heating element is provided with suitable spaced terminals 20 extending upwardly through the wall 5 of the hood for accommodating a conventional type of plug 21 on one end of an electric cord 22. The other end of the cord 22 may be provided with any suitable means such as the pronged plug 23 or insertion in a wall outlet or the like for supplying current to the electric heater.

From the foregoing then it will be seen that I have devised a comparatively simple electric heater structure, that can be readily applied to pipes and the like for heating fluid passing therethrough and that the heater is capable for use on the water pipe of the water cooling system of an internal combustion engine, on the intake manifold of the internal combustion engine, or can be readily applied to the crank case of an internal combustion engine by the employment of suitable brackets (not shown) and in the manner easily within the skill of a mechanic to serve as a heater for the oil in the crank case, and thus the heater can be used for almost any and all pipe conduits.

Even though I have herein shown and described the preferred embodiments of the invention, it is to be understood that the same is susceptible of further changes, modifications and improvements coming within the scope of the appended claims.

Having thus described my invention, what I claim as new is:

1. A heater comprising in combination a hood substantially semi-circular in cross section, heating means arranged in said hood, said hood being hollow to provide a chamber for accommodating said heating means, and said hood adapted to embrace a water pipe or the like, and oppositely disposed members hinged to the hood and adapted to swing inwardly toward one another for substantially closing the open side of the hood and to engage with the pipe conduit for securing the hood in position thereon.

2. A heater comprising in combination a hood substantially semi-circular in cross section, heating means arranged in said hood, said hood being hollow to provide a chamber for accommodating said heating means, and said hood adapted to embrace a water pipe or the like, and oppositely disposed members hinged to the hood and adapted to swing inwardly toward one another for substantially closing the open side of the hood and to engage with the pipe conduit for securing the hood in position thereon, and yieldable means for retaining said hinged members in the last referred to position.

3. A heater comprising a semi-cylindrical hood provided with a substantially closed chamber, a heating element arranged in said

chamber, a pair of oppositely disposed members hinged to the hood and adapted to be swung inwardly for substantially closing one side of the hood, a substantially V-shaped handle member, means for connecting the ends of said handle member to said hinge members, and a loop member engaging opposite portions of said handle member and movable longitudinally relative thereto for controlling swinging movement of said hinged members.

4. A heater comprising in combination a hood, an electrical heating element arranged in said hood, a pair of oppositely disposed members hinged to said hood, and normally expanded compressible means engaging said members for yieldably retaining said members in a closing position relative to the open side of said hood.

5. In combination with a water pipe connecting a vehicle radiator with the water jacket of an internal combustion engine, a hood receiving between opposed portions thereof said pipe, a heating element arranged in the hood, members hinged to said oppositely disposed portions of the hood, and yieldable means connecting said hinged members for urging the same inwardly towards one another for retaining the hood on said pipe.

In testimony whereof I affix my signature.

WALTER J. BRADFISH.
